ELECTRIC MUSICAL INSTRUMENT

Bernardus Willem van Ingen Schenau, Eindhoven, Netherlands, assignor to Hartford National Bank and Trust Company, Hartford, Conn., as trustee

Application July 20, 1946, Serial No. 685,197
In the Netherlands December 23, 1943

Section 1, Public Law 690, August 8, 1946
Patent expires December 23, 1963

3 Claims. (Cl. 84—1.19)

1

This invention relates to an electric musical instrument in which the tones are produced by oscillators made operative and inoperative by means of keys, the frequency of each tone being determined by an LC-circuit.

Instruments of this kind are known, such as electric organs, which are equipped, for example, with 96 oscillators. Although these are already materially less expensive and in addition more practical than real pipe organs, there is nevertheless the drawback that they are too voluminous and too heavy to permit an easy displacement while the cost for private persons is, as a rule, too high.

The present invention purports to construct a similar instrument which can be easily carried by one person and which is in addition very inexpensive, while the reproduction approaches that of a normal church organ both with regard to volume and quality.

It is known that the various tones in an oscillator may be obtained by that one of the elements, for example the capacity of the LC-circuit, is varied in value, which may be effected by switching on and off condensers.

The instrument according to the invention, wherein the latter principle is used, exhibits the characteristic that only such a number of oscillators is available as tones must be capable of being struck simultaneously. Consequently, the number of oscillators will rarely have to be more than 10 whilst in the case of an instrument which has not to satisfy too high requirements and which is, for example, highly appropriate to home-study, 4 to 5 oscillators suffice. This can be realized by that all the keys are connected to at least one of the oscillators whereas the other oscillators are coupled to several keys, as a rule to most keys. Furthermore, on striking one of the keys there is always only one of the oscillators made operative while on striking a second key simultaneously with the first, a second oscillator is influenced, on striking three keys the third oscillator, etc.

The instrument according to the invention may be of a very compact construction and have a small weight so that it can be easily displaced. It is thus possible to utilize the instrument also in open-air meetings and the like without particular conveying means being required. Besides, the instrument may be realized so inexpensive that it becomes within reach of everybody and is thus also suitable for home-study of a pianist or organist. It is also possible to construct a separate foot pedal for organs accord-

2

ing to the invention in which are, for example, only two oscillators and which can be used with a small pipe organ or harmonium.

The above-mentioned inventive idea may be worked out more fully as follows. For example, the instrument will be so constructed that in the position in which no keys are struck, series-connections of switches are connected in parallel with the mutually identical inductances of the LC-circuits of all the oscillators, condensers being switched between the corresponding points of each switch, hence for example the fixed contact points and the connecting lead, common to all the oscillators, between the last switch and the inductance. In this case the corresponding condensers of the various oscillatory circuits are identical to one another and the corresponding switches are connected to one and the same key. By the term "corresponding condensers" is understood the condensers which have one of their contact points, for example, between the first and the second switch, as viewed from the oscillator. Similarly, the term "corresponding switches" is understood to mean the first, the second and the third switch respectively in each oscillatory circuit. Furthermore, the construction is such that, when one key is operated, the moving contact piece of all the switches of this key but for one is connected to the fixed contact piece of every next switch of this key. On striking a key it is thus possible to make a definite oscillator operative by means of one of the switches associated with this key and also to connect the other oscillators to the switches of the next key by means of the other switches belonging to the said key. These oscillators are thus kept in readiness to be made operative when pushing one of the next keys. Since we have started from the assumption that always only a limited number of keys need be struck simultaneously, it is evident that with the same limited number of oscillators any desired combination of the corresponding number of tones is possible in the above-described manner.

At least, in order to economize in the number of condensers required, it is advisable that the keys in the range that is least used, i. e. for example the range of low tones, should be coupled to less oscillators than in the other range. This may be carried out in steps, i. e. for the highest tones the keys may be connected to all the oscillators, underneath to one less, still lower again to one less, and at last for the lowest tones to only a single oscillator. Consequently, in the last-mentioned case only one of the oscillators is

connected to all the keys whereas the other oscillators are coupled to several keys, substantially to most keys.

In order that the invention may be more clearly understood and readily carried into effect, it will be described more fully by reference to the accompanying drawings.

Fig. 1 shows an oscillator circuit utilized in a musical instrument according to the invention.

Fig. 2 shows a diagram of some keys and their circuit according to the invention.

Figs. 3, 4 and 5 show a portion of the circuit of Fig. 2 with one, two and three keys struck, and their operation.

At last, Fig. 6 shows diagrammatically a simplified circuit of a key-board.

Fig. 1 shows a simple known circuit of an oscillator having an LC-circuit which is constituted by an inductance L and a condenser C_v . The points 1 and 2 are further connected to an amplifier and a reproduction device. C is the grid condenser and R_1 the leakage resistance. R_2 serves to give the tone produced a good sinusoidal shape and must have a high value (for example 2 megohms). At last, L_1 is the feedback coil. When C_v is varied, different tones are produced. This variable condenser is in practice replaced by several capacities, for which purpose points 3 and 4 are connected to a circuit shown in Fig. 2.

The point 5 of Fig. 2 is connected to the points 4 of the various oscillators while the points 6 each correspond to one of the points 3 of these oscillators, for example O_1 , O_2 , O_3 , O_4 and O_5 . When the keys 11, 12, 13, etc. are not struck, a series-connection of switches such, for example, as for O_5 : 20, 21, 22, etc. is in parallel with the inductances of each of the oscillators. The corresponding contact points of these switches, in the present instance 23, 24 and 25, are connected, via the condensers 30e, 31e and 32e, to the connecting lead 40, common to all the oscillators, of the last switch 26 via point 5 to the inductance. The corresponding switches of the various oscillators are mounted on the same key, for example on 11. These keys are of insulating material, so that there is no electric contact between the switches. The keys 11, 12, 13, 14, 15 and 16 may be moved up and down by means of levers (not shown) which are connected to the key-board of the musical instrument. If a key is not struck it is in the position of rest such, for example, as 11. If a key is struck it goes up as shown at 14. In this case the switches are lifted at the points 27, since they are secured to the keys so as to be pivoted at the points 28. As can be seen in the drawing, the moving contacts of all switches but for one have contacted with the fixed contacts 29 of the next switch of this key. At last, this figure shows the groups of condensers 30, 31, 32, 33, 34 and 35. In each of these groups the condensers, which are further indicated by a , b , c , d and e , are identical to one another, but from group to group they are different. In group 30 the condensers are variable, for example realized as trimmers, and serve to be able to tune the instrument.

The operation of the instrument on striking one or more keys will now be further explained with reference to Figs. 3, 4 and 5.

Fig. 3 shows the circuit of Fig. 2 of which, however, only the key 13 together with the group of condensers 32 is shown and in which this key is in the struck position. The switches 22 are up so that the short-circuit of the oscillator O_1 via

the line 40 is interrupted. Now, the condensers in the LC-circuit of this oscillator can operate and also determine the frequency of the tone produced. The condensers cooperating for this purpose are: 32a and the condensers 30a and 31a which are here not shown (see Fig. 2 and the short-dash-line in Fig. 3). The other oscillators remain short-circuited since the switch which at first short-circuited O_1 , now through-connects O_2 and the switch which at first through-connected O_2 , now connects O_3 to one of the switches of the next key, etc. (long dash-line, long-short dashline, long-short-short dashlines in Fig. 3). What was described for key 13 also applies to any other key, so that O_1 is always made operative.

In Fig. 4, the two keys 12 and 15 are shown in the struck position with the two groups of condensers 31 and 34. As before, O_1 oscillates with the condensers 30a and 31a in the LC-circuit, due to which it produces a tone higher than that in the case of Fig. 3. Now, however, by the key 15 in cooperation with the key 12, the short-circuit of O_2 also is eliminated (long dashline) which oscillates with the condensers 30b, 31b, 32a, 33a and 34a in the LC-circuit. Since the condensers of each group are identical to one another and hence 30b=30a and 31b=31a the frequency of this tone is lower than the previous one. The oscillators O_2 , O_4 and O_5 are invariably short-circuited (see long-short and long-short-short dash-lines). Consequently, when a second key beside the first is struck, O_2 is always made operative. Fig. 5 shows three keys 11, 13 and 15 in the struck position with the corresponding groups of condensers 30, 32 and 34. O_1 oscillates through 30a and O_2 through 30b, 31a and 32a (short and long dash-lines). By means of key 15 in cooperation with the other two keys 11 and 13, the short circuit of oscillator O_3 is also eliminated (see long-short dash line) which oscillator O_3 then produces a tone pitch of which is determined by the condensers 30c, 31b, 32b, 33a and 34a. It is observed that, when the key 13 alone is struck (Fig. 3) O_1 produces a tone which is determined by the condensers 30a, 31a and 32a. When this key is struck simultaneously with key 11 (Fig. 5), O_2 is set thereby into oscillation, with the condensers 30b, 31a and 32a. Since 30a=30b, this key, although different oscillators and different condensers are made operative, produces in either case the same tone, such as it should be.

Consequently, if at first key 13 and subsequently key 11 is struck, the same tone is reproduced at first by O_1 and subsequently by O_2 . If, at last, key 12 is also struck, O_3 reproduces the same tone via the condensers 30c, 31b and 32a and O_2 produces a tone via 30b and 31a.

It is evident that the condensers 30 must have such values that the highest tone that is desired to produce is determined by them. For this purpose the condensers must have a great accuracy and can, as previously mentioned, be realized as trimmers, in order to be able to tune the instrument. The condensers 31, 32 etc. need be only small since they are always only operative in cooperation with the preceding one. In addition, however, and this is another particular advantage of the above-described circuit, these further condensers need have no accuracy at all since the tone is already determined by the sum of one of the condensers 30 with one or more of the following, each of which constitutes only a small portion of them. The advantage particularly resides in the fact that for these condensers use

may be made of ordinary factory condensers which are allowed to exhibit differences of 5%.

At least, Fig. 6 is a diagrammatic view of a whole key-board. In this case the keys 41 are indicated by single lines. Since, as a rule, of the keys for the lower tones a smaller number is struck simultaneously, it suffices in practice to connect these keys to less oscillators. This may be effected in steps, as can be seen from Fig. 6, so that at the left of the point 42 only four, at the left of 43 only three, at the left of 44 only two, and at the left of 45 only one oscillator can be set into oscillation at a time. This may be extended or restricted as desired. The advantage is that a smaller number of condensers is required. It is evident that in this case only one of the oscillators is connected to all the keys and the other oscillators are connected to most keys. If it is desired to produce two tones simultaneously also in the lowest range, two of the oscillators must be coupled to all the keys.

It is evident that instead of the condensers several inductances may be switched into the circuit, the constant inductances in this case having to be replaced by constant capacities.

In addition to the circuits shown, other circuits may occur in the instrument, for example for frequency doubling and the like for the stops of an organ or particular circuits to produce a piano-tone.

What I claim is:

1. In an electrical musical instrument playable by keys and adapted to generate simultaneously a predetermined number of tones, the combination comprising a plurality of electronic oscillators whose number corresponds to said predetermined number, each oscillator being provided with a like inductor forming one element in a parallel-resonant circuit, the inductors of said oscillators having one end thereof interconnected, a like plurality of identical switching systems each constituted by a chain of serially-connected switches having a fixed contact and a movable contact normally engaging said fixed contact, the movable contact of each switch in the chain being connected to the fixed contact of the succeeding switch, the fixed contact of the first switch in the chain being connected to the other end of a respective inductor and the movable contact of the last switch in the chain being connected to the interconnection of said inductors, a multiplicity of identical groups of condensers, said multiplicity being equal in number to the number of switches constituting said chain, the condensers forming each group having substantially different values and being equal in number to said predetermined number, the condensers of the different groups having

progressively different values, the corresponding condensers of said groups being connected between respective fixed contacts in the chain of switches in one of said systems and said interconnection, and means operatively coupling corresponding switches of said systems to a respective key of said instrument, the corresponding switches being banked whereby the operation of said key caused the movable contacts of each of said switches to engage the fixed contact of the succeeding switch in the bank excepting for the movable contact of the last switch which is disengaged.

2. An electrical musical instrument adapted to generate simultaneously a predetermined number of tones comprising a plurality of oscillators whose number corresponds to said predetermined number, a series of playable keys, switching means electrically coupling said keys to said oscillators and so connected that on striking any one key in said series always the same one of said oscillators is activated and on simultaneously striking the succeeding key in said series always the same one and the same another of said oscillators is activated, and a plurality of frequency determining elements connected to said switching means for insertion in said oscillators when said keys are struck, said elements being arranged to produce a distinct oscillatory tone for each key in said series.

3. The combination, as set forth in claim 1, wherein the predetermined number of tones which the instrument is adapted to generate includes a range of higher tones and a range of lower tones and wherein, in order to reduce the number of circuit components entailed for the instrument thereof are connected with each of the lower lower tones, fewer of the oscillators in the plural-tone keys than for the higher tone keys.
